CONTROL SYSTEM

Arthur M. Trogner, East Stroudsburg, Pa., assignor to Wired Radio, Inc., New York, N. Y., a corporation of Delaware

Application October 31, 1939, Serial No. 302,106

7 Claims. (Cl. 175—320)

This invention relates to control systems responsive to frequency, and more particularly to systems employing a frequency-responsive relay circuit; for example, the systems disclosed by the present applicant in Patent No. 1,949,590, issued March 6, 1934; and Patent No. 1,972,501, issued September 4, 1934.

In such systems a signal or impulse of given frequency is sent to a controlling device which is adapted to respond to that frequency and thereby provide a desired control of other apparatus. However, it sometimes happens that extraneous impulses containing the control frequency, or impulses of a transient nature, cause faulty and undesired operation.

The main object of this invention is to make a control system selective between a control frequency alone and an impulse or band of frequencies containing the control frequency.

A related object is to make a control system responsive to a given frequency, only when that frequency is not accompanied by other frequencies or impulses.

A further object is to nullify the effects of extraneous impulses on a frequency-responsive relay circuit.

These and other objects are accomplished, in the main, by providing an additional controlling device which is responsive to frequencies other than the control frequency but is not responsive to the control frequency, and by making the control of other apparatus dependent upon non-operation of said additional device.

The invention will be more clearly understood from the following description of one illustrative form thereof in connection with the accompanying drawing in which:

Fig. 1 is a diagram of a preferred embodiment of the invention; and

Figs. 2 and 3 are attenuation curves of filters A and B, respectively, in Fig. 1.

In the drawing, reference character 5 indicates an ordinary electric power circuit or branch thereof. Filter A has its input connected to circuit 5 and has its output connected to a sensitive relay 6. If it is desired that such relay be a direct current or a polarized type, a rectifier 7 is connected between the filter and relay.

In accordance with the invention, a second filter B also has its input connected to circuit 5 and has its output connected to a second sensitive relay 8, through a rectifier 9 if desired. The back contact 10 of relay 8 is connected by a conductor 11 to the front contact 12 of relay 6, thus providing a normally closed contact and a nor-

mally open contact, respectively, in a series circuit. This circuit begins with conductor 13 (which is connected to one side of power circuit 5) thence through conductor 14, armature 15 of relay 8, contact 10, and conductor 11, to contact 12 where the circuit normally is open between contact 12 and armature 16 of relay 6; thence by conductor 17 to a control relay 18, from which the circuit returns through a condenser 19 and current limiting resistance 20 to the other side of power circuit 5.

The normally closed back contact 21 of relay 6, together with armature 16 thereof and conductor 17, short-circuits the coil of relay 18 when relay 6 is not energized. A hold-in circuit for relay 18 is provided from conductor 13, through conductor 23 to armature 24 and front contact 25 of said relay where the hold-in circuit normally is open. When relay 18 is energized this circuit is completed through the relay coil, condenser 19, and resistance 20 to power circuit 5.

Another armature 21 of relay 18 is connected to conductor 23 and is adapted to close a control circuit through front contact 28 and conductor 29 to controlled devices 30, the control circuit being energized through conductors 13 and 31 which are connected to opposite sides of power circuit 5. Devices 30 may be anything controllable by electric power, such as motors, power relays, switches, lamps, heaters, etc. or control mechanisms such as described in the patents above mentioned.

In operation, the control of devices 30 is effected as follows: A control frequency or signal which may be, for instance, 3,000 cycles, is superposed on the power circuit 5 at the central station or other remote control point and is received at filter A. This filter readily passes the control frequency or a narrow frequency band, but highly attenuates all other frequencies, as illustrated in Fig. 2. The received control frequency, after being rectified, energizes relay 6 thereby operating armature 16 to close the series circuit (above described) whereby relay 18 is energized. Energization of relay 18 operates armature 24 to close its hold-in circuit (above described) thereby holding the relay closed and relieving armature 16 and contact 12 of that function. At the same time, armature 21 closes the control circuit (above described), thereby supplying power to the devices 30.

It will be observed that the received control frequency is also impressed on filter B, but its attenuation curve as shown in Fig. 3 is such that the control frequency is not capable of passing

through the filter so as to energize relay 8. However, frequencies either higher or lower than the control frequency can pass through filter B and operate relay 8. Hence, in the event a band of 5 frequencies, transient current, or an extraneous impulse is received (such as is capable of operating relay 6 in spite of the selective nature of filter A), relay 8 will attract its armature 15 and thereby open the series circuit at contact 10 before relay 6 has time to close said circuit at contact 12. Such operation of relay 8 prevents energization of relay 18 and thus prevents undesired or accidental operation of the system even though a received impulse contains the control frequency 10 among others. If, however, the proper control frequency alone is impressed on filter A and operates relay 6, a subsequent impulse operating relay 8 through filter B will have no effect, because the hold-in circuit of relay 18 will then be closed and will keep relay 18 energized as long as the proper control frequency is present on power circuit 5.

When the control frequency ceases, armature 16 of relay 6 drops back and closes back contact 21, thereby short-circuiting the coil of relay 18 as described above. This de-energizes relay 18, whereupon its armatures 24 and 27 open their contacts at 25 and 28, respectively, and the control power is removed from devices 30.

It is apparent from the above that only the proper control frequency alone is capable of causing relay 18 to operate, inasmuch as relay 8 is responsive to all other frequencies which may cause faulty or accidental operation of 35 relay 6.

It may be desirable, in some cases, to provide a slight time delay on relay 6 in order to be sure that relay 8 operates more quickly, but ordinarily this is not necessary because relay 8 40 has only to open its back contact 10 to prevent operation of relay 18, whereas relay 6 has to move its armature 16 all the way to contact 12 in order to energize relay 18.

While a preferred embodiment of the invention has been shown and described, it is to be understood that the invention is susceptible of use in many control systems and with various modifications within the scope of the appended 45 claims.

What is claimed as new and original to be secured by Letters Patent of the United States is:

1. A relay system comprising, a first relay and a second relay, a circuit for energizing said

relays, a first filter connected between said circuit and first relay to prevent operation of the latter except by current of substantially a given frequency, a second filter connected between said circuit and second relay to permit operation of the second relay by currents above and below the given frequency but to prevent operation thereof by current of substantially the given frequency, and a circuit controlled by said relays, said circuit including contacts of both relays 10 connected in series.

2. The combination defined by claim 1, and means for nullifying the effect of said second relay in the event of prior operation of said first relay.

3. In combination, a circuit comprising a normally open contact, a normally closed contact and a current operated device all connected in series, means for closing the first contact in response to a given frequency to energize said device, and means for opening the second contact in response to frequencies other than the given frequency but not in response to the given frequency alone, whereby the latter means prevents energization of said device in response to 20 a band of frequencies including the given frequency.

4. The combination defined by claim 3, including an arrangement for opening the second contact prior to closing of the first contact in 30 response to a band of frequencies.

5. The combination defined by claim 3, and a hold-in circuit for said current operated device whereby opening of the second contact while the first contact is closed has no effect on said 35 device.

6. The combination defined by claim 3 comprising in addition, means for continuing the energization of said current operated device after initial closure of said first contact, and means 40 for de-energizing said device upon cessation of the given frequency.

7. In a control system the combination of, a first control means responsive to a given frequency, a second control means responsive to 45 frequencies other than the given frequency but not responsive to the given frequency, a device controlled by both said means whereby said device is actuated only in response to the given frequency alone, and means for nullifying the effect of one of said control means in the event of the prior operation of the other of said control means.

ARTHUR M. TROGNER.
